EXTRACTIVE DISTILLATION PROCESS

Paul Munk, Berkeley, Calif., assignor to California Research Corporation, San Francisco, Calif., a corporation of Delaware

Application December 6, 1954, Serial No. 473,072

2 Claims. (Cl. 260—674)

This invention relates to an extractive distillation process for recovering substantially pure aromatic compounds from hydrocarbon distillate fractions containing the desired aromatic compound along with other aromatic as well as nonaromatic constituents, the invention finding particular application in the recovery of benzene from catalytic reformates.

The established specifications for substantially pure (nitration grade) aromatic compounds such as benzene, toluene and xylene are such as to permit the presence of only trace amounts of other aromatic compounds (as well as of nonaromatic contaminants) than the desired product if the product is to meet the required distillation range specifications. This is borne out by the fact that the presence of as little as 0.1% of the next higher aromatic, in the case of either benzene or toluene, is sufficient to bring the boiling range to the limit of the specification which calls for a distillation range of 1° C., initial to dry. Since the distillate fractions initially obtained following various petroleum refining and other operations which are productive of aromatic products normally contain substantial amounts of more than one aromatic compound (along with various nonaromatic materials), the practice which is now followed by a large segment of the industry is to redistill such fractions under rigorous conditions whereby a fraction is obtained which contains the desired aromatic compound but is free of other aromatic contaminants. Thus, in the case of the benzene-containing fraction recovered from a catalytic reforming operation, which normally contains a substantial amount of toluene along with associated nonaromatic components, the practice is to subject this fraction to one or more preliminary fractional distillation steps designed to provide a benzene heart cut which is substantially free (less than 0.1% by volume in terms of the benzene content) of any toluene, and to thereafter subject this concentrate to an extractive distillation treatment whereby contaminating nonaromatic components are removed overhead, while the bottoms, which contain the benzene along with the extractive solvent, are then distilled so as to recover substantially pure benzene.

The foregoing method has the disadvantage that a heart cut which contains but a single aromatic compound and is free of contaminating aromatic components can only be obtained by a practice of the most exacting techniques involving the use of high reflux ratios and distillation columns containing as many as 75 to 80 or more trays, thereby greatly adding to the cost of the recovery procedure. To remedy this and other deficiencies of the process described above and to otherwise provide a generally superior method for recovering pure aromatics, there is disclosed in co-pending application Serial No. 448,456 of Robert S. Worthington and Harrison M. Lavender, Jr., filed August 9, 1954, a method whereby the reformate is distilled under such relatively non-severe conditions as to provide a heart cut which not only contains the desired aromatic component (e. g., benzene)

2

but also a minor percentage (usually from about 0.5 to 5%, in terms of the weight of the desired aromatic compound) of a higher boiling aromatic compound present in the reformate, as well as various non-aromatic contaminants. Thus, with benzene, the higher boiling contaminant will normally be toluene. Such a heart cut, which can readily be obtained by the use of simple and relatively inexpensive fractionating equipment is then passed, along with a higher boiling extractive solvent (e. g., phenol), to an extractive distillation column where the lighter nonaromatic components of the feed are taken overhead while the aromatic components, along with any remaining nonaromatic contaminants, are withdrawn as bottoms. The bottoms are then passed to a solvent stripping column from which the desired aromatic component is taken overhead in the pure state, while the bottoms are recycled back to the extractive distillation column.

This method, while constituting a decided step forward in the art, has the disadvantage that the higher boiling aromatic component (e. g., toluene) present in the heart cut feed to the extractive distillation column builds up in the solvent recycle stream and thus imposes an added burden on the system in addition to reducing the capacity of the unit when solvent recycle facilities or extractive distillation column capacities are limiting factors. While the method of the aforesaid co-pending application in part overcomes this disadvantage by diverting a portion of the bottoms from the stripping unit to a second stripping column where the nonsolvent components are taken overhead and from which the solvent bottoms are returned to the main solvent recycle stream, it has been found that even when as much as 10% of the bottoms are diverted to the second stripper, the solvent recycle stream to the extractive distillation column will still contain approximately 10% by volume of the aromatic component as the system comes to equilibrium. Doubling the amount of bottoms diverted (i. e., to 20%) still leaves approximately 5% aromatics in the recycle stream, while the value is reduced to a level of about 2 to 3% even by passing 40% of the bottoms from the first to the second stripping column. While this latter amount of contaminant can be tolerated in some instances, it would be desirable if the same could be reduced to the level of 0.5 to 1.5%. Further, in the interests of economy of operation it is desirable to maintain this low aromatics content while restricting the feed to the secondary stripping column to an amount equivalent to no more than about 15% of the volume of the bottoms normally taken out of the first stripping column, and preferably this percentage should be reduced to 10% or less.

The present invention, which has as its object, among others, the overcoming of the above-recited disadvantages of the process described in the said co-pending application, rests on the discovery that said process can be practiced in such a fashion that the aromatic content of the solvent recycle stream to the extractive distillation column is reduced to negligible proportions by employing as the feed to the second stripping column a vapor side cut taken from a lower zone in the first, or primary solvent stripping column. By operating in this fashion it is possible to maintain the concentration of the aromatic contaminant (e. g., toluene) in the solvent recycle stream to the extractive distillation unit at a level below about 1.5% by volume, while still limiting the feed to the second stripping column to a relative amount not exceeding about 15% of that withdrawn as bottoms from the first stripping column.

While the process has been described above in its broader aspects, the invention is especially applicable to the preparation of individual pure aromatic compounds,

such as benzene, from catalytic reformate fractions, particularly "Platformates" derived by the catalytic reforming of naphtha fractions over a platinum-alumina reforming catalyst. In this process, as it applies to the production of benzene, a petroleum naphtha fraction consisting essentially of a mixture of naphthenic, paraffinic and aromatic hydrocarbons having from six to seven carbon atoms in the molecule, after being contacted in the vapor phase with a platinum-alumina reforming catalyst under suitable conversion conditions to largely convert the naphthenic hydrocarbons containing six carbon atoms to benzene and the seven carbon atom naphthenic hydrocarbons to toluene, and to largely isomerize the straight carbon chain paraffinic hydrocarbons to branched chain compounds, is fractionally distilled in one or more columns to produce a benzene heart cut containing substantially all of the benzene of the conversion product, along with nonaromatic components and from about 0.2 to 5% by volume of toluene, based on the volume of benzene in the concentrate. Following the preparation of the concentrate, the latter is extractively distilled in the presence of a suitable solvent (e. g., phenol) under such conditions that the relatively lower boiling nonaromatic components are separated as an overhead product, while all of the benzene and toluene, along with the higher boiling nonaromatic portion of the concentrate, is withdrawn as bottoms. Thereafter, the bottoms are passed to a benzene stripping column at an elevated temperature adapted to distill benzene of the desired purity overhead without vaporizing the other components of the feed, while a vapor side cut rich in toluene is taken between about the first and eighth trays and passed to a second, or toluene stripping column, the bottoms from said benzene stripping column, containing less than about 1.5% by volume of toluene, being recycled to the extractive distillation column for admixture with the incoming benzene concentrate. From the toluene stripping column, a stream made up predominantly of toluene, but also containing minor percentages of benzene and C₇ naphthenes, is taken overhead and returned to the benzene heart cut still (identified as a re-run column in the drawing) while the bottoms are combined with those obtained from the benzene stripping column.

While phenol has been given above as an example of an extractive solvent, and is, in fact, the preferred solvent for use in this invention when recovering benzene or toluene, a wide variety of other solvents can be employed. In general, the solvent selected should have a boiling point which is well above the end point of the stock being treated and which can thus be readily separated from the dissolved components. Thus, suitable solvents which can be employed in a practice of this invention are: phenol, aniline, cresylic acids, alkyl phenols, various polyglycols including di-, tri- and tetraethylene glycol, carbitols, diethanolamine, nitrobenzene, quinoline, furfural alcohol, furfural, monoglycerol ethers, resorcinol, xylidine, acetone and acetone-water mixtures.

The process of the present invention can be illustrated in one embodiment thereof by reference to the appended drawing wherein the figure represents a flow diagram of a process for the catalytic reforming of a hydrocarbon feed, and particularly for the recovery of pure benzene from the resulting reformate.

In the drawing, a feed mixture comprising a petroleum naphtha fraction consisting primarily of a mixture of naphthenic, paraffinic and aromatic hydrocarbons having from 6 to 7 carbon atoms in the molecule is passed in the vapor phase through line 10 into reforming zone 11 wherein the feed comes into contact with a reforming catalyst under elevated conditions of temperature and pressure suitable for effecting the desired conversion of C₆ naphthenes to benzene and the C₇ naphthenes to toluene, and to largely isomerize the straight-chain paraffinic hydrocarbons present to branched-chain com-

75 pounds. From the reforming zone the resulting reformate passes through line 12 into a stabilizer column 13 provided with a suitable reboiler 14, from which column the lighter fractions comprising predominantly C₃—C₄ hydrocarbons are taken overhead through line 15 and condenser 16, with a portion of said lighter hydrocarbons being sent to product recovery through line 17, while the balance is returned as reflux to the column through line 18.

10 The bottoms from stabilizer column 13 are withdrawn through line 19 and passed into a topping still 20 provided with a reboiler 21. From this still a lighter fraction comprising essentially C₅ and C₆ hydrocarbons boiling below hexane is taken overhead through line 22 and condenser 23, with a portion of the condensate being sent to product recovery through line 24, while the balance is returned to the column as reflux through line 25.

15 The bottoms from the topping still 20 are withdrawn through line 26 and charged into a mid-portion of a re-run column 30 provided with a reboiler 31. From this column a benzene heart cut fraction is taken overhead through line 32 and condenser 33, which fraction contains substantially all of the benzene supplied to the column, as well as toluene in an amount equal to from about 0.2 to 5% by volume, based on the benzene content of the fraction, along with a substantial proportion of nonaromatic components. Of the resulting condensate, a portion is returned to the column as reflux through line 34, while the balance of the stream is passed through line 35 into a mid-point of an extractive distillation column 36 having a reboiler 38. The balance of the toluene introduced into re-run column 30 through line 26 is removed from said column through line 37, along with nonaromatic hydrocarbons boiling above benzene, and is sent to a suitable toluene recovery system (not shown).

20 In a representative run, the benzene concentrate in line 35 contains 28.6% benzene, 1.4% toluene and 70% nonaromatics, and is supplied to the extractive distillation column 36 at a rate of 1000 volumes per day, with phenol being introduced to the column through line 50 at a rate of 1400 volumes per day. The temperature in column 36 is so regulated that the hydrocarbons boiling below benzene are taken overhead through line 39 and condenser 40 at a rate of 3800 volumes per day, with 3100 volumes per day being returned to the column as reflux through line 42, while a raffinate stream amounting to 700 volumes per day is sent to a suitable recovery system (not shown) through line 41, said raffinate (at a still head temperature of 178° F. and under the described reflux conditions) consisting of 96.4% nonaromatics and but 3.6% benzene.

25 The bottoms from the column 36, which contain the desired benzene along with associated higher boiling aromatic (toluene) and nonaromatic contaminants, as well as the solvent, are supplied to a mid-point of a benzene stripper column 44 provided with a reboiler 45. From the column 44 (when operated, for example, at a still head temperature of 183° F. and at reflux ratio of about 6 to 1), a benzene stream consisting of 99.2% benzene and 0.8% nonaromatics is taken overhead through line 46 and condenser 47 at a rate of 1680 volumes per day, of which 280 volumes is discharged through line 48, while the balance is returned to the column as reflux through line 49. The stream in line 48 may, if desired, be passed to a treating zone where the benzene is subjected to the conventional finishing treatments required for the production of a product of nitration grade.

30 The major portion of the phenol solvent introduced into column 44 is withdrawn as bottoms through line 50 at a temperature of about 390° F. and recycled to the extractive distillation column 36. The balance of the solvent is withdrawn through line 51 as a vapor side cut rich in toluene, this line being positioned between the fifth and sixth trays of column 44. Specifically, 1280 volumes per

day of bottoms, at a temperature of 390° F. and containing approximately 1% by volume of toluene, are withdrawn through line 50, while the side cut in line 51, taken at about 375° F. totals 138 volumes per day and is made up of 120 volumes phenol, 12 volumes toluene, and 3 volumes benzene with nonaromatic components representing the balance. The product in line 51, preferably after being cooled to a temperature of about 360° F., is passed to a mid-point of toluene stripping column 52 provided with a reboiler 53. From this column an overhead stream at a temperature of 235° F. is taken through line 54 and condenser 55 at a rate of approximately 54 volumes per day of which 36 volumes is returned to the column as reflux through line 56, while the balance is withdrawn through line 57. The bottoms from column 52, consisting essentially of phenol, are withdrawn through line 58 at a temperature of about 390° F. and at a rate of 120 volumes per day, this stream being joined with that in line 50 for recycle to column 36.

However, the overhead product withdrawn through line 57 at a rate of 18 volumes per day (made up of 12 volumes toluene, 3 volumes benzene, and the balance consisting predominantly of naphthenic constituents) is returned to column 30 via line 26. In this fashion, the toluene and benzene components of the overhead stream from the toluene stripping column 52 are retained in the system for eventual recovery through the benzene and toluene offtake lines 48 and 37, respectively.

While in the foregoing description the vapor side cut line 51 from the benzene stripping column has been positioned between the fifth and sixth trays of that column, the position of this line may be varied somewhat, as from about the first to the eighth tray, preferably from the fourth to the eighth tray, depending on the conditions encountered within a particular unit. Thus, it is desirable to obtain a vaporous side cut fraction which is relatively low in the solvent component as well as in that taken overhead from the column, yet which is as rich as possible in the aromatic contaminant, i. e., toluene in the case of the unit described above. Thus, if the line is positioned higher than about the seventh or eighth trays in the column, the side cut obtained becomes unduly rich in the overhead component (i. e., benzene), while if the line is positioned below about the fourth tray, the product recovered in line 51 becomes unduly rich in the phenol or other solvent component employed and thus tends to overload the second stripping column 52, although this may be preferable to increasing the recycle of the overhead component, here benzene.

In the foregoing description, the various percentages given are on a volume basis. Further, in the flow diagram various of the required pumps, heat exchangers, valves and other items of flow control equipment have been omitted in the interests of simplicity and clarity of expres-

sion, the placement of such auxiliary equipment being evident to those skilled in the art.

While the character of this invention has been described in detail and numerous illustrative examples given, this 5 had been done by way of illustration only and with the intention that no limitation should be imposed upon the invention thereby. It will be apparent to those skilled in the art that numerous modifications and variations may be effected in the practice of this invention which is of the 10 scope of the claims appended hereto.

I claim:

1. In a process for recovering substantially pure benzene from a catalytic reformate containing benzene, toluene and nonaromatic components, the steps comprising 15 freeing the reformate of lighter nonaromatic hydrocarbon constituents; passing the resulting bottoms product so obtained to a re-run column from which a concentrate containing substantially all the benzene content of said reformate, along with nonaromatic components and from 20 about 0.2 to 5% by volume of toluene, is taken overhead, and from which a fraction comprised in major portion of toluene is withdrawn as bottoms; passing said concentrate to an extractive distillation column, and there contacting the concentrate with a selective solvent at elevated temperatures whereby the relatively low boiling nonaromatic components are separated as an overhead product, while withdrawing a bottoms product containing substantially all the benzene and toluene content of 25 the concentrate, along with solvent; passing said bottoms product to a benzene stripping column maintained at a temperature adapted to distill the benzene overhead while 30 withdrawing as bottoms a solvent fraction low in toluene, and, from a lower zone of said stripping column, a vaporous side cut relatively rich in toluene; passing said 35 side cut to a toluene stripping column maintained at a temperature adapted to distill overhead the toluene and other nonsolvent components present, while withdrawing as bottoms a solvent fraction; recycling said toluene-containing overhead fraction to the rerun column; and re- 40 cycling the bottoms from said stripping columns to the extractive distillation column.

2. The process of claim 1 wherein the selective solvent employed in the extractive distillation column is phenol.
